UNITED STATES PATENT OFFICE.

JOSIAH RECORD, OF MANKATO, MINNESOTA.

SUSPENSION CARRIER APPARATUS.

SPECIFICATION forming part of Letters Patent No. 728,294, dated May 19, 1903.

Application filed February 9, 1903. Serial No. 142,661. (No model.)

To all whom it may concern:

Be it known that I, JOSIAH RECORD, a citizen of the United States, residing at Mankato, in the county of Blue Earth and State of Minnesota, have invented a new and useful Suspension Carrier Apparatus, of which the following is a specification.

This invention relates to devices or apparatus for conveying articles between widely-separated points by means of suspended bearing or supporting cables or wires, and has for its object to simplify the construction and the operating means for devices of this character; and the invention consists in certain novel features of construction, as hereinafter shown and described, and specified in the claims.

In the drawings illustrative of the invention, in which corresponding parts are designated by like denoting characters, Figure 1 is a longitudinal sectional elevation of one of the receptacles, together with a portion of the suspension-cables and one of the supports. Fig. 2 is a transverse section of the same. Fig. 3 is a plan view of a section of the cables and one of the supporting devices. Fig. 4 is a view illustrating the arrangement for running around curves or turning corners.

This invention may be employed for conveying small articles from place to place regardless of the distance, and will preferably be arranged for operation by electric power, but may be operated by any other suitable power.

The device is intended more particularly for use in conveying merchandise to and from the farm and including the transportation of cream to and from the creameries, cheese factories, and the like, but which may be employed for conveying any objects or form or quality of material required.

The bearing cables or wires are arranged in parallel lines spaced apart and supported at suitable intervals, as by posts, the bearing-cables supporting the receptacles for containing the material or objects to be transported and the posts likewise supporting spaced guide cables or wires to insure the retention of the receptacles in position upon the bearing-cables. The bearing-cables are represented at 10 11 and may be of any suit-

able strength or size, according to the load they are to support. The supporting-posts 12 will be arranged at suitable intervals and will each be provided with a bracket-arm 13, 55 extending therefrom beneath the cables and provided with projecting standards 14 15, spaced apart to correspond to the cables, as shown. Upon the upper ends of the standards are secured, respectively, curved arms 60 16 17, extending laterally in opposite directions from the standards and in longitudinal alinement with the cables and provided with grooves 18 19 in their upper surfaces to receive and support the cables, as shown. 65 One of the receptacles is shown at 20 and consists of a preferably oblong box or casing having transverse spaced shafts or axles 21, carrying grooved wheels 22, running upon the cables. The receptacles are divided into a 70 lower compartment 23, preferably extending longitudinally of the receptacles, and a plurality of upper compartments 24, superimposed upon the lower compartment, and with a transverse chamber 25 between the upper 75 compartments and providing for the reception of an inlet-pipe 26, whereby liquid substances or compounds may be fed to the lower compartment independently of the upper compartments. The compartments 24 will 80 be provided with movable covers 27, and the intermediate chamber 25 will likewise be provided with a movable cover 28, so that the whole receptacle may be closed and the contents protected and the receptacle present a 85 symmetrical appearance. The inlet-pipe 26 will preferably be provided with a detachable cap 29, and when this is removed a funnel may be connected to the pipe, through which the liquid may be supplied to the lower compartment. The lower compartment is designed for holding cream or other liquid or semiliquid material and is supplied with a discharge-pipe 30, having a controlling-valve 90 31, as shown. The upper compartments are 95 designed to hold any kind of merchandise and may be of any desired size, and any number may be provided. The receptacles will be further supported by spaced guides or cables or wires 32 33, which are held in place 100 by clips 34 35, connecting them to the standards 14 15, the clips having set-screws 36 37,

whereby they may be adjusted longitudinally of the standards.

The receptacle 20 is provided with grooved bearing-wheels 38 39, running underneath the guide-cables 32 33, disposed centrally of the receptacle, as shown. By this arrangement it is obvious the receptacle will be guided and held in place upon the cables 10 11 and prevented from displacement therefrom by 10 the coaction of the guide-cables and grooved guide-wheels.

The motor for moving the receptacles upon the cables may be located at any suitable point, but will preferably be placed in a separate 15 compartment 40 at one end at the lowest possible point to provide the greatest weight below the cables to secure the proper "balance." The motor will preferably be an approved form of electric motor, and the cables 10 11 20 will preferably be utilized as conductor and return mediums for the currents, the connection being in the usual and well-known manner. A conventional form of motor is indicated at 41 and will be coupled by the usual 25 gearing (represented at 42) to the axle 21. The wiring between the motor and axle is not shown, as its arrangement is so well known and as it forms no part of the present invention.

30 When running around curves or corners, the curved arms 16 17 will be turned with the curves horizontal, as indicated in Fig. 4, to serve as carriers for the cables and guide the wheels and receptacles around curves or corners.

35 The brackets 13 will be provided with diagonal braces 43, as shown, to enable them to withstand the weight of the cables and receptacles.

40 The cables will be suitably stretched between the terminals; but as this stretching means is no part of the present invention it is not illustrated.

45 The parts may be of any suitable material, but will preferably be of metal, and the compartment 23 will preferably be lined with non-corrosive material to prevent deleterious ac-

tion upon the cream or other delicate susceptible substances or materials.

Having thus described the invention, what 50 is claimed is—

1. In a suspension cable carrier apparatus, spaced support-brackets extending from posts and having vertical spaced standards projecting therefrom, and curved supports having 55 longitudinal wire-engaging recesses and extending laterally from said standards, substantially as described.

2. In a suspension cable carrier, spaced supports, brackets extending from said supports and having spaced standards projecting therefrom, curved bearing-wire supports extending laterally from said standards and having wire-engaging grooves, and guide-wire-supporting means connected to said 65 standards between said brackets and grooved bearing-wire supports, substantially as described.

3. In a suspension cable carrier, spaced supports, brackets extending from said supports and having spaced standards projecting therefrom, curved bearing-wire supports extending laterally from said standards and having wire-engaging grooves, and clips adjustably connected to said standards between said 70 brackets and carrier-wire supports, and adapted to adjustably support the spaced guide-wire of the carrier-receptacle, substantially as described.

4. In a suspension cable carrier apparatus, 80 a receptacle comprising a lower compartment extending longitudinally thereof and spaced upper compartments having the inlet to said lower compartment disposed between said spaced upper compartments, substantially as 85 described.

In testimony that I claim the foregoing as my own I have hereto affixed my signature in the presence of two witnesses.

JOSIAH RECORD.
